UNITED STATES PATENT OFFICE.

JOHN WALDHEIM, OF ELIZABETH, NEW JERSEY, ASSIGNOR TO UNDERWOOD COMPUTING MACHINE COMPANY, OF NEW YORK, N. Y., A CORPORATION OF NEW YORK.

COMPUTING MACHINE.

Application filed December 11, 1920. Serial No. 429,838.

To all whom it may concern:

Be it known that I, JOHN WALDHEIM, a citizen of the United States, residing in Elizabeth, in the county of Union and State of New Jersey, have invented certain new and useful Improvements in Computing Machines, of which the following is a specification.

This invention relates to the registers of computing machines, particularly those of the type known as the Underwood standard bookkeeping machine, by which both typewriting and computing operations may be effected.

Broadly stated, the object of the invention is to provide means for indicating to the operator the kind of computing operation which has taken place and been run up on the number-wheels; for example, whether an adding or a subtracting operation has been run up, and, so far as the present invention is concerned, regardless of whether the result of a subtraction operation is of a positive or of a negative character.

The present invention comprises means for indicating to the operator the character of a computing operation which has been run up on the number-wheels of a register. The present invention further comprises means automatically operated concomitantly with the running up of the numbers on the number-wheels, for thereby indicating the kind of computing operation, such as addition or subtraction, which has taken place.

More particularly, according to the present invention, this indication is given by varying the color of the light reaching the eye of the observer from the number-wheels. Also, according to the present invention, the light may be supplied from suitable electric lamps for illuminating the numeral-bearing faces of the number-wheels, and means may be provided for automatically extinguishing these lamps when all of the number-wheels

of the register stand at the zero position. In the Underwood standard bookkeeping machine, the number-wheels are rotated in one direction only by means of rack-bars, subtraction being accomplished by what is known as the "complemental method," a complemental bar being provided adjacent the number-wheel of lowest denomination, and which moves forward one step farther in running up the result of a subtracting operation than it does during an adding op-

eration. In carrying out the present invention, advantage is taken of this additional movement of the complemental bar, and the complemental bar is employed for operating the indicating means. According to a further and more particular feature of the invention, the complemental bar may operate a circuit-controller in control of the lighting circuits for two lamps of different distinctive colors, for lighting one of the lamps to indicate that an addition operation has been run up on the number-wheels, and for lighting the other lamp of different color to indicate that a subtraction operation has been run up on the number-wheels, the arrangement being such that one of the lamps will be extinguished concomitantly with the lighting of the other lamp.

Other features and advantages will hereinafter appear.

In the accompanying drawings, Figure 1 is a partial front-to-rear vertical section of the front part of an Underwood standard bookkeeping machine embodying the present invention, with the parts of the mechanism thereof in position for indicating an addition operation, and also in the position corresponding to the zero position of all the number-wheels, and, therefore, with both register lamps extinguished.

Figure 2 is a similar enlarged view, partly diagrammatic and with parts omitted, showing the parts of the device as being moved to the subtraction-indicating position, just at the completion of such movement.

Figure 3 is a view similar to Figure 2, showing the indicating device as set at the subtraction-indicating position and about to be moved back to the addition-indicating position.

Figure 4 is a partial elevation, as viewed from the right in Figure 3 and as indicated by the arrow.

Figure 5 is a diagram of the electric circuits and mechanical parts involved, with both register lamps extinguished, corresponding to the zero position of all the number-wheels.

In the Underwood standard bookkeeping machine in part illustrated in the accompanying drawings, and in which the present invention is embodied, a totalizer or register is shown which includes, as usual, a plurality of coaxially-arranged number-wheels 1, all of these number-wheels being substan-

2

tially alike, and each having the usual series of digits or numerals upon its periphery, which forms the numeral-bearing face of the number-wheel. The number-wheels 1 are journaled on a shaft 2 and are rotated in one direction only by means of rack-bars 3, meshing with pinions 4 which may have the usual one-way connection with the number-wheels 1. For holding the number-wheels 1 at any indicating positions to which they may be moved, each of these number-wheels is provided with detent teeth 5 between which yieldingly engages a spring-pressed detent 6 pressed to the engaging position by a retractile spring 7, the detent 6 being pivoted on a rod 8 which is parallel to the number-wheel shaft 2. Two of the adjacent teeth 5 of each number-wheel 1 are cut away to provide therein recesses 9, thereby to permit the detent 6 to seat more deeply between these two adjacent teeth at the zero position of the number-wheels, for a purpose pertinent to the present invention which will hereinafter appear. The machine has the usual frame 10 and casing 11, having therein a sight-opening or window, closed by a glass 12, in position for reading the indication given by the line of numerals visible therethrough on the numeral-bearing peripheral faces of the number-wheels 1. The sight-opening or window may be properly restricted, particularly as to its width, by means of a marginal shield 13 at the back of the glass plate 12 forming the window.

The Underwood standard bookkeeping machine is constructed to perform both adding and subtracting operations as may be desired, and for effecting a subtraction operation, what is known as the complementary method is employed, as is fully described in prior patents, among which may be mentioned the patent to Hans Hanson, No. 1,278,812, dated September 10, 1918, and the patent to John N. Thornton, No. 1,283,360, dated October 29, 1918. In performing a subtraction operation by the complementary method, the number-wheels 1 are rotated in the same direction as in performing an addition operation, but for effecting subtraction these number-wheels are rotated to an extent equal to the complement of the numbers corresponding to the numeral-keys struck. In the machine illustrated in the drawings, the rack-bars 3 are driven by a general operator (not shown) in the usual manner, and the additional step of rotation is imparted to the lowest denominational number-wheel 1 by means including a supernumerary or complementary bar 14 adjacent to this number-wheel. Said complementary bar 14 is driven forwardly at each actuation of the general operator and moves idly and always the same distance during an addition operation. During a subtraction

operation, however, the complementary bar 14 is driven about one digit distance further forwardly and is also effective to drive the rack-bar 3, of the lowest denominational number-wheel, one digit distance further than the number set on said rack-bar, to make up for the mathematical error of "1," in the lowest denominational position, which is characteristic of the complementary method. This complementary bar 14 thus moves this additional step regardless of whether the subtraction operation produces a positive or a negative result. In carrying out the present invention, the device now to be described for indicating whether an adding or a subtracting operation has been run up on the number-wheels is controlled by the complementary bar 14. In the form of the invention illustrated in the accompanying drawings, such indication is given by varying the color of the light reaching the eyes of the operator through the window 12 from the numeral-bearing peripheral faces of the number-wheels 1.

In the form of the invention illustrated in the drawings, lighting means are provided for illuminating the peripheral numeral-bearing faces of the number-wheels 1, automatically-operated means controlled by the complementary bar 14 being provided for changing the color of the light reflected from the number-wheels for thereby giving the desired indication. Such lighting means comprise a pair of miniature incandescent lamps 15 and 16 within the casing 11, respectively just at the front and rear of the sight-opening 12, and held in place by clamps 17 and 18 secured to the casing 11. These register lamps 15 and 16 are of distinctively different colors; for example, the forward lamp 15 may emit a white light, while the rear lamp 16 emits a red light. The white lamp 15 and the red lamp 16 may have lamp circuits or lighting circuits independently established therefor, and these lamp circuits may be connected in multiple relation to main conductors 19 and 20, including in the main circuit a suitable resistance 21, which may be a desk lamp, as indicated in Figure 5, and the main circuit may also include a manually-operable switch comprising a movable contact member or switch-lever 22 co-operative with a stationary contact member 23, for opening the main circuit, when desired, to extinguish all of the lamps.

The lighting circuit for the white indicating lamp 15 includes a conductor 24 connecting this lamp to the main conductor 19, and further includes conductors 25 and 26 leading respectively from the lamp 15 and from the other main conductor 20. The conductor 25 is connected to an upright spring member 27, which at its upper end carries a contact terminal 28, and the conductor 26 is connected to an upright spring

member 29, which at its upper end carries a movable contact terminal 30. The contact terminals 28 and 30 are supported adjacent each other but out of contact, and the movable contact terminal 30, which is yieldingly supported by its spring 29, may be moved into contact with the contact terminal 28 for thereby closing a lighting circuit for the white lamp 15, as shown at the left in Figures 1 and 5, and when the movable contact terminal 30 is released, it will be automatically moved by its spring 29 to the open circuit position thereof diagrammatically shown in Figures 2 and 3. Similarly, the red lamp 16 may be included in a lighting circuit comprising a conductor 31 connecting the lamp 16 to the main conductor 19, and conductors 32 and 33 leading respectively from the lamp 16 and from the other main conductor 20, the conductor 32 being connected to an upright spring member 34 which carries at its upper end a contact terminal 35, and the conductor 33 being connected to an upright spring member 36 which at its upper end carries a movable contact terminal 37 normally positioned adjacent to, but in spaced relation from, the contact terminal 35. The movable contact terminal 37, which is resiliently supported by its upright spring member 36, may be moved into contact with the adjacent contact terminal 35 for thereby electrically connecting the main conductors 19 and 20 through the red lamp 16 to establish a lighting circuit for this lamp, as shown at the right in Figures 2 and 3. When the movable contact terminal 37 is released, it will move automatically, by reason of the resiliency of its supporting spring 36, to the open circuit position shown at the right in Figures 1 and 5. The contact terminals 28 and 30 for the white lamp 15 form a pair, and a similar pair is formed by the contact terminals 35 and 37 for the red lamp 16, and these two pairs of contact terminals are spaced some distance apart, in a front-to-rear direction, with the movable contact terminals 30 and 37 located at the inner sides of the pairs. The lower ends of the respective upright spring members 27, 29, 34 and 36 are rigidly secured, in individually insulated relation, to an insulating base plate 38, and the base plate 38 is supported upon a bracket 39 secured to the inner side of the casing part 11.

The movable contact terminals 30 and 37 are controlled by a circuit-controlling device operated by the complemental bar 14 and including a switch-lever 40 pivoted near its middle upon a pivot-pin 41, carried by a supporting bracket 42, which is rigidly secured to, and projects forwardly from, the inner side of the front wall of the casing 11. The lower end of the switch-lever 40 is provided on the front and rear

with insulating blocks 43 for engaging the movable contact terminals 30 and 37, for moving these terminals to their circuit-closing positions. The upper end of the switch-lever 40 is turned over laterally to form a transverse end part 44, which may lie in the path of the advancing front end of the complemental bar 14 as this bar moves forward an additional step in effecting a subtracting operation, as hereinbefore noted. The switch-lever 40 will be maintained at either of its circuit-closing positions by means of a comparatively strong retractile spring 45, which at its upper end is anchored to a stud 46 projecting from the bracket 42 above the upper end of the switch-lever 40 and vertically in line with the pivot-stud 41, and at its lower end the spring 45 is connected to a pin 47 projecting from the switch-lever 40 near the lower end thereof. The arrangement is such that the spring 45 pulls on the switch-lever 40 at one side of its pivot 41 in one circuit-closing position of this lever, and pulls on the other side of the pivot 41 in the other circuit-closing position of the switch-lever 40, so that thereby the switch-lever 40 will be maintained at each of its circuit-closing positions, for lighting either the white lamp 15 or the red lamp 16, while the circuit of the other lamp remains open.

Normally, or for effecting adding operations, the switch-lever 40 will be maintained by its spring 45 at the forwardly-inclined position, shown in Figures 1 and 5, thereby to provide for the lighting of the white lamp 15. While running up on the number-wheels 1 the results of an adding operation, the complemental bar 14 will move idly forward from the full-line position thereof shown in Figure 1 to the dot-and-dash line position there indicated, at which position the forward end of the complemental bar will come to rest just about in contact with the transversely-bent upper end 44 of the switch-lever 40, so that no movement will be imparted to the switch-lever. However, in running up the results of a subtracting operation, the complemental bar 14 will move forward one step farther, substantially to the position shown in Figure 2, and in doing so its forward end will engage with and push forward the turned-over upper end 44 of the switch-lever 40, thereby rocking the switch-lever 40 to the forwardly-inclined position shown in Figures 2 and 3, in which it will be maintained by its spring 45, and thereby closing the lighting circuit for the red lamp 16 and opening the lighting circuit for the white lamp 15, whereby the red light from the lamp 16 will indicate that a subtracting operation has been run up on the number-wheels 1.

Means are provided for restoring or resetting the switch-lever 40 from the subtrac-

tion-indicating position thereof, shown in Figures 2 and 3, back to the addition-indicating position thereof, shown in Figures 1 and 5. For this purpose, a yieldingly mounted 5 pawl-member 48 is pivoted at its forward end on the switch-lever 40, below and somewhat to the front of the pivot 41 thereof, and projects rearwardly from the switch-lever, and has a transversely-turned end 49, which may 10 come in the path of a downwardly-projecting lug 50 formed on the forward end of the complementary bar 14. The pawl-member 48 is pressed upwardly by a spring 51 and normally into contact with a stop-pin 52 projecting from the switch-lever 40, so that the 15 pawl-member 48 normally projects rearwardly from the switch-lever 40 substantially at right angles thereto, as shown in Figures 1 and 3. In running up the result of a subtracting operation, the complementary bar 14, as hereinbefore noted, will continue its forward movement beyond the dot-and-dash line position thereof shown in Figure 1, to the additional-step position thereof shown in Figure 2. The downwardly-projecting lug 50 on the complementary bar 14, in this further movement, will pass just above the transversely-turned end 49 of the pivoted pawl-member 48, so that, as the complementary bar 20 14 continues its forward movement, carrying with it the upper end 44 of the switch-lever 40, the spring 51 will yield and permit the switch-lever 40 to move pivotally relatively to the pivoted pawl-member 48, over the 25 transverse end 49 of which the lug 50 on the complementary bar 14 will slide, as shown in Figure 2.

When the complementary bar 14 is retracted rearwardly upon the return movement of 40 the general operator, the pivotally-mounted pawl-member 48 will be snapped back by its spring 51 into contact with its stop-pin 52, as shown in Figure 3. In this position of the movable parts of the circuit-controlling device, the laterally-projecting end 49 of the pawl-member 48 will lie in the path of the lug 50 as the complementary bar 14 is moved forward to run up the next succeeding result, which may be that of an adding operation. 45 In such case, the lug 50 on the complementary bar 14 will strike against the end 49 of the pivoted pawl-member 48 and will rock the switch-lever 40 in a clockwise direction from the subtraction-indicating position thereof, 50 shown in Figures 2 and 3, to the addition-indicating position thereof, shown in Figures 1 and 5. During this resetting operation, the switch-lever 40 and the pawl-member 48 move as a unit, the pawl being maintained 55 in engagement with the pin 52 by the spring 51. The final part of each rocking movement of the switch-lever 40, of course, is assisted by the spring 45.

It is evident from the foregoing description 60 that, when the switch-lever 40 is in the

rearwardly-inclined position thereof, shown in Figures 1 and 5, a lighting circuit is provided from the main conductors 19 and 20 to the white lamp 15, for thereby indicating that an adding operation has been run up on 70 the number-wheels 1, and that the lighting circuit for the red lamp 16 will be in an open condition. Conversely, it is evident that, when the switch-lever 40 is in its forwardly-inclined position, shown in Figures 2 and 3, 75 a lighting circuit will be provided from the main conductors 19 and 20 to the red lamp 16, for thereby indicating that a subtracting operation has been run up on the number-wheels 1, while the white lamp 15 will be 80 extinguished.

As a feature of the present invention, means are provided, controlled by the number-wheels 1, for extinguishing the register-lamp 15 or 16, as the case may be, when all 85 the number-wheels stand at zero, and for lighting one of these register-lamps when any number-wheel is moved away from its zero position. In order to obtain this result, a short circuit is provided between the main 90 conductors 19 and 20 leading to the register-lamps, and this short circuit is opened for lighting one of the register-lamps when any 95 number-wheel 1 of the register is moved away from its zero position. In the subsequent 100 computing operations, either the white lamp 15 will be lighted, or the red lamp 16, depending upon whether the result of an adding operation or the result of a subtracting operation is run up on the number-wheels, through the movement of the usual 105 general operator, as above described.

The short circuit for the register-lamps 15 and 16 includes conductors 53 and 54 leading respectively from the main conductors 19 and 20. The short circuit, through the conductors 53 and 54, is normally maintained in open condition by means of a transverse bail-member 55 universal to all of the detents 6 and having at its ends rock-arms 56 pivoted 110 on the pivot-rod 8 for the detents 6. The upper end of one of the bail-arms 56 engages a strip 57 of insulating material between a stiff spring plate 58 and a flexible spring plate 59, the lower ends of the insulating 115 strip 57 and plates 58 and 59, which form contact terminals, being secured by a screw 60 to the usual front bar or rail of the frame 10. The contact springs 58 and 59 are insulated from the frame 10 by means of insulating members 61 through which the screw 60 passes. The movable contact terminal or flexible contact spring 59 has a rearwardly-turned upper end 62, which is normally in circuit-closing contact with the upper end 120 of the stationary contact terminal or stiff contact spring 58. The universal bail-member 55 may act through the insulating strip 57 to move the contact-making spring end 62 of the flexible spring 59 away from the 125 130

stiff spring 58, thereby to open the short circuit which includes the conductor 53 connected to the stiff spring 58 and the conductor 54 connected to the flexible spring 59.

5 When all of the number-wheels 1 are brought to their zero positions, all of the detents 6 will be moved by their springs 7 into the recesses 9, thereby permitting the universal bail-member 55 to be moved, by 10 means of springs 63 connected thereto and one of which is shown in Figure 1, to a rearward position which will enable the upper contact-making end 62 of the flexible spring 59 to move into contact with the upper end of the stiff spring 58, thereby completing the short circuit through the conductors 53 and 54 and extinguishing whichever of the register-lamps 15 or 16 may have been lighted. The detent-receiving notches 20 between all the remaining number-wheel teeth 5, corresponding to the digits "1" to "9", inclusive, are of sufficiently small dimensions to cause the detents 6 to hold the universal bail-member at a forward position in which 25 it holds the contact-making end 62 of the flexible contact spring 59 out of engagement with the stiff spring 58, thereby closing the lighting circuit through either the white register-lamp 15 or the red register-lamp 16 30 whenever any one of the number-wheels 1 stands away from its zero indication. When the short circuit is closed around the register-lamps 15 and 16, the resistance of the desk-lamp 21 will prevent an objectionable 35 rush of current through the main conductors 19 and 20.

The manually operable switch-lever 22 provides for lighting or extinguishing the desk-lamp 21, as well as the register-lamps 40 15 and 16, subject to control of these register-lamps, as above described.

The means above described for controlling the register-lamps for thereby indicating to the operator whether or not the register stands at zero is substantially the same as that disclosed in the application for patent of Frank W. Blake, Serial No. 384,312, filed May 26, 1920 (now Patent No. 1,438,914, dated December 5, 1922). The 50 present invention, embodying therein features of the prior invention, indicates to the operator whether the register is out of use, and whether, when in use, an adding or a subtracting operation has been run up.

55 It will be understood that the machine may be changed from the state of addition to that of subtraction in the usual way, as in the Underwood bookkeeping machine, by state-setting means which may include a 60 key (not shown), or may be set automatically, as shown in the Thornton patent herein referred to, to set the machine for subtraction; the machine being automatically set to addition by the actuation of the 65 general operator. It will further be under-

stood that the complementary bar 14 is dependent for its effect, to actuate the adjacent rack bar 3, on the subtraction-setting mechanism. Consequently, it follows that the means to indicate the kind of computation 70 that has been run into the register is, to some degree, dependent on the state-setting means.

Variations may be resorted to within the scope of the invention, and portions of the 75 improvements may be used without others.

Having thus described my invention, I claim:

1. In a computing machine, the combination of a register comprising number-wheels 80 for indicating the results of different kinds of computing operations, and automatically-operated means to indicate the kind of result run up on the number-wheels.

2. In a computing machine, the combination of a register comprising number-wheels 85 for giving indications of different kinds of computing operations, and means automatically operated concomitantly with the running up of the numbers to indicate the kind 90 of computation which has taken place.

3. In a computing machine, the combination of a register comprising number-wheels 95 for indicating different kinds of computing operations, and automatically-operated means for varying the color of the light reaching the eye of the observer from the number wheels for thereby indicating the kind of computing operation which has taken place.

4. In a computing machine, the combination of a register comprising number-wheels 100 for indicating different kinds of computing operations, lighting means for illuminating the numeral-bearing faces of the number-wheels, and automatically-operated means for varying the color of the light from said lighting means reaching the eye of the observer by reflection from the number-wheels for thereby indicating the kind of computing 105 operation which has taken place.

5. In a computing machine, the combination of a register comprising number-wheels 110 for indicating different kinds of computing operations, lighting means for illuminating the numeral-bearing faces of the number-wheels, means for extinguishing the lighting means when all of the number-wheels reach the zero position and for lighting the lighting means when any one of the number-wheels is moved away from its zero position, and automatically-operated means for varying the color of the light from said lighting means reaching the eye of the observer by reflection from the number-wheels for 115 thereby indicating by the color of the light the kind of computing operation which has taken place.

6. In a computing machine, the combination of a register comprising number-wheels 120 125

and means to indicate the character of the result to be read from the number-wheels, including means for changing the color of the light received by the eye of the observer 5 from the number-wheels when the character of said result is changed.

7. In a computing machine, the combination of a register comprising number-wheels for giving indications of adding and subtracting operations, and automatically-operated means to indicate whether an adding or a subtracting operation has been run up on the number-wheels.

8. In a computing machine, the combination of a register comprising number-wheels for giving indications of adding and subtracting operations, and means automatically operated concomitantly with the running up of the numbers to indicate whether 20 an adding or a subtracting operation has taken place.

9. In a computing machine, the combination of a register comprising number-wheels for giving indications of adding and subtracting operations, and automatically-operated means for varying the color of the light reaching the eye of the observer from the number-wheels for thereby indicating whether an adding or a subtracting operation 50 has taken place.

10. In a computing machine, the combination of a register comprising number-wheels for giving indications of adding and subtracting operations, lighting means for illuminating the numeral-bearing faces of the number-wheels, and automatically-operated means for varying the color of the light from said lighting means reaching the eye of the observer by reflection from the number-wheels for thereby indicating by the color of the light whether an adding or a subtracting operation has taken place.

11. In a computing machine, the combination of a register comprising number-wheels for giving indications of adding and subtracting operations, means including rack-bars for actuating the number-wheels in one direction only, a complementary bar adjacent the number-wheel of lowest denomination and which moves a greater distance in running up a subtracted number than it does when an added number is run up, and means controlled by the complementary bar for indicating whether an adding or a subtracting operation has been run up on the number-wheels.

12. In a computing machine, the combination of a register comprising number-wheels for giving indications of adding and subtracting operations, means including rack-bars for actuating the number-wheels in one direction only, a complementary bar adjacent the number-wheel of lowest denomination and which moves a greater distance in running up a subtracted number than it does

when an added number is run up, lighting means for illuminating the numeral-bearing faces of the number-wheels, and means controlled by the complementary bar for varying the color of the light from said lighting means reaching the eye of the observer by reflection from the number-wheels for thereby indicating by the color of the light whether an adding or a subtracting operation has been run up on the number-wheels.

13. In a computing machine, the combination of a register comprising number-wheels for giving indications of adding and subtracting operations, means including rack-bars for actuating the number-wheels in one direction only, a complementary bar adjacent the number-wheel of lowest denomination and which moves a greater distance when a subtracted number is run up than it does when an added number is run up, lighting means for illuminating the numeral-bearing faces of the number-wheels, means controlled by the number-wheels for extinguishing the lighting means when all of the number-wheels stand at the zero position and for lighting the lighting means when any one of the number-wheels is moved away from its zero position, and means controlled by the complementary bar for varying the color of the light from said lighting means reaching the eye of the observer by reflection from the number-wheels for thereby indicating by the color of the light whether an adding or a subtracting operation has been run up on the number-wheels.

14. In a computing machine, the combination of a register comprising number-wheels for giving indications of adding and subtracting operations, means including rack-bars for operating the number-wheels in one direction only, a complementary bar adjacent the number-wheel of lowest denomination and which moves a greater distance in running up a subtracted number than it does when an added number is run up, an electric lamp of one color for illuminating the numeral-bearing faces of the number-wheels, another electric lamp of a different color also for illuminating the numeral-bearing faces of the number-wheels, a lamp circuit in which said first lamp may be included to light the lamp, a second lamp circuit in which said second lamp may be included to light the lamp, and means including a circuit-controlling device operated by the complementary bar for concomitantly opening one of the lamp circuits and closing the other, and vice versa, thereby to indicate by the color of the lamp which is lighted whether an adding or a subtracting operation has been run up on the number-wheels.

15. In a computing machine, the combination of a register comprising number-wheels

- for giving indications of adding and subtracting operations, means including rack-bars for operating the number-wheels in one direction only, a complemental bar adjacent to the number-wheel of lowest denomination and which moves a greater distance in running up a subtracted number than it does when an added number is run up, an electric lamp of one color for illuminating the numeral-bearing faces of the number-wheels, another electric lamp of a different color also for illuminating the numeral-bearing faces of the number-wheels, a lamp circuit in which said first lamp may be included to light the lamp, a second lamp circuit in which said second lamp may be included to light the lamp, and means including a circuit-controlling device operated by the complemental bar for concomitantly opening one of the lamp circuits and closing the other, and vice versa, thereby to indicate by the color of the lamp which is lighted whether an adding or a subtracting operation has been run up on the number-wheels; said circuit-controlling device comprising a pair of open contacts in said first lamp circuit, a similar pair of open contacts in said second lamp circuit, and a pivoted switch lever operated by the complemental bar for closing one of said pairs of contacts in the addition position of the complemental bar and for closing the other of said pairs of contacts in the subtraction position of the complemental bar.
16. In a computing machine, the combination of a register comprising number-wheels for giving indications of adding and subtracting operations, means including rack-bars for operating the number-wheels in one direction only, a complemental bar adjacent to the number-wheel of lowest denomination and which moves a greater distance in running up a subtracted number than it does when an added number is run up, an electric lamp of one color for illuminating the numeral-bearing faces of the number-wheels, another electric lamp of a different color also for illuminating the numeral-bearing faces of the number-wheels, a lamp circuit in which said first lamp may be included to light the lamp, a second lamp circuit in which said second lamp may be included to light the lamp, and means including a circuit-controlling device operated by the complemental bar for concomitantly opening one of the lamp circuits and closing the other, and vice versa, thereby to indicate by the color of the lamp which is lighted whether an adding or a subtracting operation has been run up on the number-wheels; said circuit-controlling device comprising a pair of open contacts in said first lighting circuit, a similar pair of open contacts in said second lighting circuit, a two-armed pivoted switch lever for closing one of said pairs of contacts in one of its pivotal positions, and for closing the other of said pairs of contacts in its other pivotal position, a spring for holding the switch lever at each of its circuit-closing positions, one arm of the switch lever being engageable by the end of the complemental bar in the greater movement of this bar in running up the result of a subtracting operation for thereby moving the switch lever from an addition-indicating to a subtraction-indicating position, and a yieldingly mounted member pivoted on the other arm of the switch lever and projecting therefrom in position to be engaged by the end of the complemental bar in the lesser movement of this bar in running up the result of an adding operation for thereby resetting the switch lever from its subtraction-indicating position back to the addition-indicating position.
17. In a computing machine, the combination of a register comprising number-wheels for giving indications of adding and subtracting operations, means including rack-bars for operating the number-wheels in one direction only to run up the numbers on the number-wheels, a complemental bar adjacent to the number-wheel of lowest denomination and which moves a greater distance in running up a subtracted number than it does when an added number is run up, an electric lamp of one color for illuminating the numeral-bearing faces of the number-wheels, another electric lamp of a different color also for illuminating the numeral-bearing faces of the number-wheels, means for establishing a lighting circuit for each lamp, means including a circuit-controlling device operated by the complemental bar in control of both lighting circuits for lighting a lamp of one color to indicate that an addition operation has been run up on the number-wheels and for lighting the lamp of another color to indicate that a subtraction operation has been run up on the number-wheels, and means including a circuit-controller controlled by the number-wheels for controlling the lighting circuits of both lamps to prevent the lighting of any lamp when all of the number-wheels are at the zero position and to provide for the lighting of a lamp when any number-wheel is moved away from its zero position.
18. In a computing machine, the combination of a register comprising number-wheels for giving indications of adding and subtracting operations, an electric lamp for illuminating the numeral-bearing faces of the number-wheels to indicate an addition operation, another electric lamp of different color also for illuminating the numeral-bearing faces of the number-wheels to indicate a subtracting operation, and automatically-operated means for lighting one of the lamps when an adding opera-

tion is run up on the number-wheels and for extinguishing the lighted lamp and lighting the other lamp when a subtracting operation is run up on the number-wheels.

- 5 19. In a computing machine, the combination of a register comprising number-wheels for giving indications of adding and subtracting operations, an electric lamp for illuminating the numeral-bearing faces of 10 the number-wheels to indicate an addition operation, another electric lamp of different color also for illuminating the numeral-bearing faces of the number-wheels to indicate a subtracting operation, automatically-15 operated means for lighting one of the lamps when an adding operation is run up on the number-wheels and for extinguishing the lighted lamp and lighting the other lamp when a subtracting operation is run 20 up on the number-wheels, and automatically-operated means to prevent the lighting of any lamp when all of the number-wheels are at the zero position and to provide for the lighting of a lamp when any number-25 wheel is moved away from its zero position.

20. In a computing machine, the combination of a register comprising number-wheels for giving indications of adding and subtracting operations, an electric lamp of one 30 color for illuminating the numeral-bearing faces of the number-wheels to indicate by such color that an adding operation has been run up on the number-wheels, another electric lamp of a different color also for illuminating the numeral-bearing faces of the 35 number-wheels to indicate that a subtracting operation has been run up on the number-wheels, means for establishing a lighting circuit for each lamp, and means conditioned by 40 the setting of the machine from a condition of addition to a condition of subtraction for extinguishing the addition-indicating lamp and concomitantly lighting the subtraction-indicating lamp, and conversely conditioned 45 for extinguishing the subtraction-indicating lamp and relighting the addition-indicating lamp when the machine is reset from the condition of subtraction to the condition of addition.
- 50 21. In a computing machine, the combination of a register comprising number-wheels for giving indications of adding and subtracting operations, an electric lamp of one 55 color for illuminating the numeral-bearing faces of the number-wheels to indicate by

such color that an adding operation has been run up on the number-wheels, another electric lamp of a different color also for illuminating the numeral-bearing faces of the number-wheels to indicate that a subtracting operation has been run up on the number-wheels, means for establishing a lighting circuit for each lamp, means conditioned by the setting of the machine from a condition of addition to a condition of subtraction for extinguishing the addition-indicating lamp and concomitantly lighting the subtraction-indicating lamp, and conversely conditioned for extinguishing the subtraction-indicating lamp and relighting the addition-indicating lamp when the machine is reset from the condition of subtraction to the condition of addition, and means including a circuit-controller controlled by the number-wheels for controlling the lighting circuits of both lamps to prevent the lighting of any lamp when all the number-wheels are at the zero position and to provide for the lighting of a lamp when any number-wheel is moved away from its zero position.

22. In a computing machine, the combination of a register comprising number-wheels for giving indications of adding and subtracting operations, and automatically-85 operated means influenced by the setting of the machine from a condition of addition to a condition of subtraction, or vice versa, to indicate whether an adding or a subtracting operation has been run up on the number-wheels.

23. In a computing machine, the combination of a register comprising number-bearing elements, and automatically-operated means comprising two lamps of different 95 colors to indicate the kind of computation run into the number-bearing elements.

24. In a computing machine to perform addition and subtraction comprising a register having number-wheels, a white light to 100 illuminate the number-wheels when an added number is run into the register, a red light, and means to automatically extinguish the white light and illuminate the number-wheels with the red light when a subtracted 105 number is run into the register.
